TREATMENT OF ANIMAL AND VEGETABLE OILS

Loran Old Buxton, East Orange, N. J., assignor
to National Oil Products Company, Harrison,
N. J., a corporation of New Jersey

No Drawing. Application July 29, 1942.
Serial No. 452,776

13 Claims. (Cl. 260—426)

This invention relates in general to the treatment of animal and vegetable oils and particularly to a process for the production of soap and high iodine value oils.

For many years linseed oil has been the oil principally employed in paints and varnishes to give them their characteristic drying properties. Because of the somewhat erratic fluctuations in the flaxseed crop, the price of linseed oil is relatively high. Because of this and other reasons, a number of substitutes for linseed oil have been proposed. Vegetable oils such as soybean oil and similar oils have been suggested, but, although they may be used in admixture with linseed oil, they are not satisfactory as they form soft, gummy films. Fish oils may also be used in conjunction with linseed oil, but even though they usually have a much higher iodine value than the vegetable oils and are fairly rapid driers, they also form soft, tacky films and are therefore no more applicable for use alone than are the vegetable oils. Much work has been done, along the line of developing new or known but not extensively grown plants for producing drying oils and also along the line of chemical processing of the relatively cheap and available oils now used in admixture with linseed oil in order to produce drying oils, but, as yet, no satisfactory, readily available, economical replacement for linseed oil for use in paints or varnishes has been developed.

In the present art of soap making, fatty materials, i. e. oils, fats, fatty acids, etc., are saponified with various alkaline metal agents. Soaps produced in such a manner usually contain as constituents thereof fatty acid radicals which contain unsaturated linkages which are relatively unstable towards oxidative changes induced by the atmosphere, light and other oxidizing influences. It is thus necessary in many instances to add to soaps of such nature various materials known as antioxidants in order to provide stable soaps. Naturally this increases the cost of such soaps and furthermore in many instances such antioxidants have deleterious effects on the soaps such as, for example, causing darkening thereof, imparting undesirable odors thereto, etc. Furthermore, any highly unsaturated constituents present in the soap tend to decrease the detergent qualities thereof. Moreover, due to the fact that soap contains a mixture of fatty acid radicals of varying chain lengths, the detergent properties of the soap are diminished since, as is well known, fatty acids of the longer chain lengths produce soaps which are not as efficient as those pro-

duced from the fatty acids of shorter length, e. g. fatty acids of twelve, fourteen, sixteen and in some instances even eighteen carbon atoms.

It is the object of this invention to provide a process for producing drying oils from semi-drying oils of vegetable and animal origin.

It is a further object of this invention to provide an improved process for increasing the iodine value of fatty materials of vegetable and animal origin.

Another object of the invention is to provide improved drying oils for use in paints, varnishes and similar materials.

Still another object of the invention is to provide a process for producing soaps which are improved in their stability toward oxidative deterioration and which have improved detergent properties.

I have found that animal and vegetable oils and fats may be selectively and partially saponified by carrying out the saponification at a comparatively slow rate under controlled conditions whereby the more saturated components and the shorter chain fatty acid components of the fatty material are more readily saponified than the less saturated components. Thus by partially saponifying such fatty materials under conditions conducive to selective saponification, it is possible to obtain a number of products, each more valuable than the fatty material itself. That fraction of the oil which is more readily saponified is the more highly saturated portion thereof and the shorter chain or lower molecular weight fatty acid components thereof. By partially and selectively saponifying the fatty material, the more highly saturated components thereof may be separated from the remainder of the fatty material and employed for such purposes as desired. This fraction is particularly applicable for the production of soaps since soaps produced therefrom contain very little, if any, highly unsaturated fatty materials. Such soaps are superior to soaps containing appreciable amounts of unsaturated fatty material since the presence of highly unsaturated fatty materials in the soap tends to lower the detergency and the stability thereof. Furthermore, there is no unsaponifiable matter present in the soap as is the case with soaps produced by the complete saponification of most fatty material. This is another factor tending to improve the quality of the soaps since, of course, any unsaponifiable matter present in the soap mass reduces to that extent the percentage of effective detergent matter. Also the unsaponifiable material in a fatty substance usually con-

tains a certain amount of undesirable odiferous substances, and a certain amount of unsaturated material which is relatively unstable and readily oxidized. The presence of such unsaponifiable material in a soap tends, of course, to lessen the desirability and stability thereof. That fraction of the fatty material which is not saponified during the selective partial saponification contains the more highly unsaponified components thereof. Such unhydrolyzed unsaturated fatty material has many valuable uses, depending to some extent, of course, upon the degree of unsaturation. The fatty material which has an iodine value of about 90 or above is particularly valuable as a drying and semi-drying oil for use in paints, 15 varnishes and similar products.

I have found that, in order to get the desired selective saponification, it is very important that the saponification reaction proceed slowly under controlled conditions. If the reaction is carried out at a fairly rapid rate, as is usually the case, e.g. in soap manufacture, the saponification will not be selective, but instead the more highly unsaturated components of the oil will be saponified as readily as the saturated components. Consequently, even though the oil may be only partially saponified, if the reaction is carried out at a fairly rapid rate, the portion of the oil which is not saponified will have practically the same degree of unsaturation as the original oil.

I have found, contrary to the general belief, that the ester linkages between the more saturated, the shorter chain and the lower molecular weight fatty acids and glycerol are not as strong as the ester linkages between the unsaturated fatty acids and glycerol; consequently, the former are more easily broken and if the conditions of saponification are properly controlled, such linkages will be ruptured whereas the linkages between the more unsaturated fatty acids and glycerol will not be broken. Then when the saponified saturated fatty acids are removed from the partially saponified mixture, the fatty material which remains will be more highly unsaturated than the original material. However, if the conditions of saponification are made somewhat more severe the unsaturated fatty acids will be split off from the glycerol just as readily as the saturated ones, and therefore in such cases the degree of unsaturation of the unsaponified fatty material, for all practical purposes, will not have been increased whatsoever.

In selectively and partially hydrolyzing the fatty material with caustic alkali, the partial saponification may be carried out without the presence of a solvent; however, it is preferred to carry out this step in the presence of a solvent for the oil, such as a hydrocarbon or halogenated hydrocarbon solvent. Suitable solvents in which the animal or vegetable oil may be selectively and partially saponified include, inter alia, ethylene dichloride, methylene dichloride, trichloroethylene, heptane, hexane, cyclohexane, methyl cyclohexane, etc., or a mixture of two or more of these or other solvents which will not dissolve any appreciable amount of water or hydrated alkali metal soap.

The oil is preferably diluted with solvent before adding the saponification agent. When the oil is diluted with solvent for carrying out the selective partial saponification step, the solvent should comprise from 15% to 99% and preferably 25% to 75% based on the weight of the oil.

The selective partial saponification of the oil is preferably effected by slowly stirring aqueous 75

caustic alkali, aqueous potassium hydroxide or sodium hydroxide being preferred, into the solvent diluted oil, care being taken to insure thorough mixing and to avoid too rapid saponification. From about 25% to about 95%, preferably from 30% to 90% of the amount of alkali theoretically required to completely saponify all of the saponifiable material contained in the oil is added.

As a relatively slow rate of saponification appears to be the most favorable for selective saponification of the more saturated fatty acids, I prefer to carry out the saponification at room temperature, i.e. without supplying extraneous heat. In some cases when saponifying at room temperature, it is desirable to employ a saponification catalyst, such as, for example, isopropanol, ethanol, methanol, etc., to aid in bringing about a reaction between the oil and the alkali. This is particularly true when saponifying in the presence of a solvent. Of course the rate of saponification may be slowed down by reducing the amount of saponification catalyst used, or by not using any at all, also by using a less concentrated alkali, etc. If desired, saponification inhibitors may be used to retard the rate of reaction; however, that is seldom necessary when the reaction is carried out at room temperature. Also, if desired the rate of saponification may be retarded by carrying the reaction out at a temperature below room temperature.

In separating the unsaponified portion of the oil from the resulting soaps, I prefer to extract the partially saponified mass with a hydrocarbon or halogenated hydrocarbon solvent, such as one of the solvents suitable for use in diluting the oil prior to the saponification step, and preferably the same solvent as was used during the saponification step. Before extracting the selectively partially saponified mass with solvent, I prefer to adjust the water content thereof to about 22% to about 26% based on the weight of the soap present in the mass, as separation of the saponified portion from the unsaponified portion is most efficiently accomplished when the moisture content of the soap mass is within this range. Of course, the oil may be separated from the soap by other means, e. g. centrifugation, etc., if desired.

Any animal or vegetable fatty material containing unsaturated fatty acid radicals may be treated by the process of the invention. Fatty materials which may be treated include, inter alia, soybeans oil, wheat germ oil, corn oil, corn germ oil, perilla seed oil, linseed oil, olive oil, teaseed oil, cottonseed oil, sesame seed oil; peanut oil, palm kernel oil, locustseed oil, coconut oil, cranberry seed oil, grapeseed oil, nut oils, e. g. walnut oil and pecan oil, grapefruit seed oil, fruit oils, lard oil, whale oil, seal oil, butter oil, porpoise oil, tomato seed oil, neat's-foot oil, etc. Also, if desired, mixtures of any of these or other animal or vegetable fatty materials may be selectively partially saponified by the process of the invention.

The following table summarizes a few of the many experiments carried out on various oils of vegetable and animal origin under varying conditions. In each case 100 parts of fatty material were saponified with an amount of 45.5% aqueous potassium hydroxide sufficient to give the percentage of saponification as indicated in the table. In each case, 3 parts of isopropanol were employed as a saponification catalyst, and the saponification was carried out at room temperature with mild agitation of the reaction mass. When

the saponification was carried out in the presence of a solvent, 50 parts of ethylene dichloride were dissolved in 100 parts of oil. Upon the completion of the partial saponification, the partially saponified mass was mixed with 300 parts of ethylene dichloride, and the mixture warmed to about 40° C. to coagulate the soaps. The moisture content of the soap was then increased to about 24-25%, and the mixture then cooled to about 25° C., and the unsaponified fraction extracted with additional batches of fresh solvent. The extracts were then filtered, and the fatty material recovered therefrom by removing the solvent by distillation under reduced pressure.

Table I

Oil	Saponifi- cation	Conditions	Iodine value	
			Original	Final
Crude wheat germ oil	25	Solvent.....	123	126
Do.....	50	do.....	123	133
Do.....	75	do.....	123	140
Raw linseed oil	52	do.....	172	184
Do.....	68	do.....	172	181
Do.....	73	do.....	172	182
Crude cotton seed oil	80	do.....	100	114
Do.....	82	No solvent.....	100	113
Refined cotton seed oil	81	Solvent.....	110	122
Do.....	83	No solvent.....	110	118
Teaseed oil	77	Solvent.....	84	89
Do.....	81	No solvent.....	84	87
Crude corn oil	72	Solvent.....	118	133
Do.....	75	No solvent.....	118	128
Crude corn germ oil	72	Solvent.....	126	132
Do.....	77	No solvent.....	126	128
Crude peanut oil	73	Solvent.....	90	97
Do.....	77	No solvent.....	90	95
Crude sesame oil	75	Solvent.....	112	119
Do.....	77	No solvent.....	112	115
Refined soybean oil	72	Solvent.....	123	136
Do.....	80	No solvent.....	123	133
Crude coconut oil	81	Solvent.....	9.1	15.5
Do.....	88	No solvent.....	9.1	12.2
Palm kernel oil	69	Solvent.....	14	25.5
Do.....	92	No solvent.....	14	24.2
Lard oil	75	Solvent.....	99	109
Do.....	81	No solvent.....	99	106
Butter oil	63	Solvent.....	28	36
Neat's-foot oil	83	do.....	69	76
Do.....	85	No solvent.....	69	74
Olive oil	72	Solvent.....	81.5	89.5
Do.....	80	No solvent.....	81.5	87
Rancid olive oil	77	Solvent.....	65	73
Crude perilla oil	43	No solvent.....	187	191
Do.....	72	do.....	187	193
Crude cranberry seed oil	65	Solvent.....	166	171

It will be noted that in every case, greater selectivity was secured by carrying out the saponification in the presence of ethylene dichloride.

From the foregoing description it is apparent that the iodine value of oils of animal and vegetable origin may be readily increased. Such products, depending upon their final degree of unsaturation, have many uses in industry such as drying oils, raw materials for the preparation of sulfated wetting agents and emulsifiers, as raw materials to be sulfurized, blown and polymerized, etc. Moreover, the soaps produced in accordance with the process of the invention are highly improved in character due to the absence of the more unsaturated components and unsaponifiable matter. The expression "animal and vegetable oils" is employed herein to connote all oils, whether classified as drying, semi-drying or non-drying, obtained from animal and vegetable origin, the latter including any form of vegetation.

Since certain changes may be made in carrying out the above process without departing from the scope of the invention, it is intended that all matter contained in the above description shall

be interpreted as illustrative and not in a limiting sense.

Having described my invention, what I claim as new and desire to secure by Letters Patent, is:

- 5 1. A process of increasing the iodine value of animal and vegetable oils which comprises partially and selectively saponifying 25% to 95% of an oil selected from the group consisting of animal and vegetable oils by means of an alkali to split saturated glycerides and separating the unsaponified fraction from the resulting mass.
- 10 2. A process of increasing the iodine value of animal and vegetable oils which comprises admixing an oil selected from the group consisting of animal and vegetable oils with a lesser quantity of a water-immiscible organic solvent therefor, saponifying 25% to 95% of the oil by means of an alkali and separating the unsaponified fraction from the saponified mass.
- 15 3. A process of increasing the iodine value of animal and vegetable oils which comprises admixing an oil selected from the group consisting of animal and vegetable oils with a lesser quantity of a hydrocarbon solvent therefor, saponifying 25% to 95% of the oil by means of an alkali and separating the unsaponified fraction from the saponified mass.
- 20 4. A process of increasing the iodine value of animal and vegetable oils which comprises admixing an oil selected from the group consisting of animal and vegetable oils with a lesser quantity of a halogenated hydrocarbon solvent therefor, saponifying 25% to 95% of the oil by means of an alkali and separating the unsaponified fraction from the saponified mass.
- 25 5. A process of increasing the iodine value of animal and vegetable oils which comprises admixing an oil selected from the group consisting of animal and vegetable oils with a lesser quantity of ethylene dichloride, saponifying 30% to 90% of the oil by means of an alkali and separating the unsaponified fraction from the saponified mass.
- 30 6. A process of increasing the iodine value of animal and vegetable oils which comprises admixing an oil selected from the group consisting of animal and vegetable oils with a lesser quantity of a hydrocarbon solvent therefor, saponifying 25% to 95% of the oil by means of an alkali in the presence of a saponifying catalyst and separating the unsaponified fraction from the saponified mass.
- 35 7. A process of increasing the iodine value of animal and vegetable oils which comprises admixing an oil selected from the group consisting of animal and vegetable oils with a lesser quantity of ethylene dichloride, saponifying 30% to 90% of the oil by means of an alkali in the presence of a small quantity of isopropanol and separating the unsaponified fraction from the saponified mass.
- 40 8. A process of increasing the iodine value of animal and vegetable oils which comprises admixing in the presence of an alcoholic saponification catalyst an oil selected from the group consisting of animal and vegetable oils having a lesser quantity of a water-immiscible organic solvent dissolved therein with a quantity of alkali sufficient to saponify 25% to 95% of said oil, stirring the mass to form a super-solvent emulsion, breaking the emulsion by means of heat to flocculate the soap, adding a further quantity of water-immiscible organic solvent to cause complete separation of the flocculated soap particles and separating the solvent solution of the unsaponified high iodine value oil from the soap particles.
- 45 9. A process of increasing the iodine value of animal and vegetable oils which comprises admixing an oil selected from the group consisting of animal and vegetable oils with a lesser quantity of a water-immiscible organic solvent dissolved therein with a quantity of alkali sufficient to saponify 25% to 95% of said oil, stirring the mass to form a super-solvent emulsion, breaking the emulsion by means of heat to flocculate the soap, adding a further quantity of water-immiscible organic solvent to cause complete separation of the flocculated soap particles and separating the solvent solution of the unsaponified high iodine value oil from the soap particles.
- 50 10. A process of increasing the iodine value of animal and vegetable oils which comprises admixing an oil selected from the group consisting of animal and vegetable oils with a lesser quantity of a water-immiscible organic solvent dissolved therein with a quantity of alkali sufficient to saponify 25% to 95% of said oil, stirring the mass to form a super-solvent emulsion, breaking the emulsion by means of heat to flocculate the soap, adding a further quantity of water-immiscible organic solvent to cause complete separation of the flocculated soap particles and separating the solvent solution of the unsaponified high iodine value oil from the soap particles.
- 55 11. A process of increasing the iodine value of animal and vegetable oils which comprises admixing an oil selected from the group consisting of animal and vegetable oils with a lesser quantity of a water-immiscible organic solvent dissolved therein with a quantity of alkali sufficient to saponify 25% to 95% of said oil, stirring the mass to form a super-solvent emulsion, breaking the emulsion by means of heat to flocculate the soap, adding a further quantity of water-immiscible organic solvent to cause complete separation of the flocculated soap particles and separating the solvent solution of the unsaponified high iodine value oil from the soap particles.
- 60 12. A process of increasing the iodine value of animal and vegetable oils which comprises admixing an oil selected from the group consisting of animal and vegetable oils with a lesser quantity of a water-immiscible organic solvent dissolved therein with a quantity of alkali sufficient to saponify 25% to 95% of said oil, stirring the mass to form a super-solvent emulsion, breaking the emulsion by means of heat to flocculate the soap, adding a further quantity of water-immiscible organic solvent to cause complete separation of the flocculated soap particles and separating the solvent solution of the unsaponified high iodine value oil from the soap particles.
- 65 13. A process of increasing the iodine value of animal and vegetable oils which comprises admixing an oil selected from the group consisting of animal and vegetable oils with a lesser quantity of a water-immiscible organic solvent dissolved therein with a quantity of alkali sufficient to saponify 25% to 95% of said oil, stirring the mass to form a super-solvent emulsion, breaking the emulsion by means of heat to flocculate the soap, adding a further quantity of water-immiscible organic solvent to cause complete separation of the flocculated soap particles and separating the solvent solution of the unsaponified high iodine value oil from the soap particles.
- 70 14. A process of increasing the iodine value of animal and vegetable oils which comprises admixing an oil selected from the group consisting of animal and vegetable oils with a lesser quantity of a water-immiscible organic solvent dissolved therein with a quantity of alkali sufficient to saponify 25% to 95% of said oil, stirring the mass to form a super-solvent emulsion, breaking the emulsion by means of heat to flocculate the soap, adding a further quantity of water-immiscible organic solvent to cause complete separation of the flocculated soap particles and separating the solvent solution of the unsaponified high iodine value oil from the soap particles.
- 75 15. A process of increasing the iodine value of animal and vegetable oils which comprises admixing an oil selected from the group consisting of animal and vegetable oils with a lesser quantity of a water-immiscible organic solvent dissolved therein with a quantity of alkali sufficient to saponify 25% to 95% of said oil, stirring the mass to form a super-solvent emulsion, breaking the emulsion by means of heat to flocculate the soap, adding a further quantity of water-immiscible organic solvent to cause complete separation of the flocculated soap particles and separating the solvent solution of the unsaponified high iodine value oil from the soap particles.

9. A process of increasing the iodine value of animal and vegetable oils which comprises admixing in the presence of an alcoholic saponification catalyst an oil selected from the group consisting of animal and vegetable oils having a lesser quantity of ethylene dichloride dissolved therein with a quantity of alkali sufficient to saponify 25% to 95% of said oil, stirring the mass to form a super-solvent emulsion, breaking the emulsion by means of heat to flocculate the soap, adding a further quantity of ethylene dichloride to cause complete separation of the flocculated soap particles and separating the solvent solution of the unsaponified high iodine value oil from the soap particles.

10. A process of increasing the iodine value of animal and vegetable oils which comprises admixing in the presence of isopropanol an oil selected from the group consisting of animal and vegetable oils having a lesser quantity of ethylene dichloride dissolved therein with a quantity of alkali sufficient to saponify 30% to 90% of said oil, stirring the mass to form a super-solvent emulsion, breaking the emulsion by means of heat to flocculate the soap, adding a further quantity of ethylene dichloride to cause complete separation of the flocculated soap particles and separating the solvent solution of the unsaponified high iodine value oil from the soap particles.

11. A process of increasing the iodine value of linseed oil which comprises admixing in the presence of isopropanol linseed oil having a lesser quantity of ethylene dichloride dissolved therein with a quantity of alkali sufficient to saponify

30% to 90% of said oil, stirring the mass to form a super-solvent emulsion, breaking the emulsion by means of heat to flocculate the soap, adding a further quantity of ethylene dichloride to cause complete separation of the flocculated soap particles and separating the solvent solution of the unsaponified high iodine value oil from the soap particles.

12. A process of increasing the iodine value of soya bean oil which comprises admixing in the presence of isopropanol soya bean oil having a lesser quantity of ethylene dichloride dissolved therein with a quantity of alkali sufficient to saponify 30% to 90% of said oil, stirring the mass to form a super-solvent emulsion, breaking the emulsion by means of heat to flocculate the soap, adding a further quantity of ethylene dichloride to cause complete separation of the flocculated soap particles and separating the solvent solution of the unsaponified high iodine value oil from the soap particles.

13. A process of increasing the iodine value of cranberry seed oil which comprises admixing in the presence of isopropanol cranberry seed oil having a lesser quantity of ethylene dichloride dissolved therein with a quantity of alkali sufficient to saponify 30% to 90% of said oil, stirring the mass to form a super-solvent emulsion, breaking the emulsion by means of heat to flocculate the soap, adding a further quantity of ethylene dichloride to cause complete separation of the flocculated soap particles and separating the solvent solution of the unsaponified high iodine value oil from the soap particles.

35 LORAN OID BUXTON.
